UNITED STATES PATENT OFFICE

ALF C. EBBESSEN, OF CHICAGO, ILLINOIS, ASSIGNOR TO ORANGE-CRUSH COMPANY, OF CHICAGO, ILLINOIS

DESIGN FOR A JAR

Application filed February 28, 1931. Serial No. 38,884. Term of patent 14 years.

To all whom it may concern:

Be it known that I, ALF C. EBBESSEN, a citizen of the United States, residing at Chicago, Illinois, have invented a new, original, and ornamental Design for Jar, of which the following is a specification, reference being had to the accompanying drawing, forming a part thereof.

The figure is a perspective view of a jar embodying my new design, the ornamentation thereon and shown in the drawing being repeated throughout.

I claim:

The ornamental design for a jar as shown and described.

ALF C. EBBESSEN.
